UNITED STATES PATENT OFFICE.

CHARLES FRANCIS ADAMS EDDY, OF SAN BERNARDINO, CALIFORNIA, ASSIGNOR OF ONE-HALF TO BENJAMIN HAMMETT NORTON, OF NEW YORK, N. Y.

FOLDABLE TRAY.

No. 914,030.

Specification of Letters Patent.

Patented March 2, 1909.

Application filed February 1, 1908. Serial No. 413,795.

To all whom it may concern:

Be it known that I, CHARLES FRANCIS ADAMS EDDY, a citizen of the United States of America, residing at San Bernardino, California, have invented certain new and useful 5 Improvements in Foldable Trays, of which the following is a specification.

The invention relates to foldable trays and more particularly to the class of knock-down 10 tray structures, which latter when in an operative position receive and support eggs. However, the same may be adapted to receive various articles of merchandise.

The primary object of the invention is the 15 provision of a foldable structure, such as a plurality of superposed perforated sheets of relatively stiff material forming trays, for receiving articles, in this instance eggs, to be supported and suspended thereby, and adapted to be removably held within a box, crate 20 or the like.

Another object of the invention is the provision of a foldable structure, such as a tray having a plurality of superposed perforated 25 sheets of relatively stiff material, each provided at opposite longitudinal sides with crease lines to form flexible intermediate and end connecting strips for said sheets of material.

30 A further object of the invention is the provision of foldable superposed perforated sheets of material forming trays for receiving eggs and having removable perforated or imperforate partitions forming separator sheets 35 and top and bottom for the trays, so as to allow the latter to be stacked one upon another for shipment of large quantities of articles, namely, eggs, in a crate, box or the like receptacle.

40 With these and other objects in view the invention, for example, consists in the construction, combination and arrangement of parts hereinafter described, and as illustrated 45 in the accompanying drawings, which disclose the preferred embodiment of the invention. However, it is to be understood that changes, variations and modifications may be made such as come properly within the scope of the claims hereunto appended, without departing from the spirit of the invention.

50 In the drawings:—Figure 1, is an enlarged perspective view of the foldable tray structure removably held within a box. Fig. 2, is 55 a transverse section of the tray structure, the

latter removed from the box. Fig. 3, is a perspective view of the tray structure in a folded position. Fig. 4, is a perspective view of a modified form of the invention. Fig. 5, is a view of the same in a folded position. 60 Fig. 6, is a view of the tray structure, showing the same, one stacked upon another and with the removable partitions between them. Figs. 7 and 8, are detail views of a partition 65 and top or cover, respectively, for the tray structures. Fig. 9, is a transverse sectional view of a further modification of the tray structure.

Similar reference characters indicate corresponding parts throughout the several 70 views in the drawings.

In the drawings, with reference particularly to Figs. 1, 2, and 3, the numeral 1, designates a foldable tray structure comprising upper sheets 2, of any suitable material, but, 75 preferably of relatively stiff card-board, which are arranged in parallel rows with respect to each other, and having perforations 3, of any desirable number, for receiving eggs. At opposite longitudinal sides of each sheet 2, 80 formed by crease lines 4, are downwardly bent connecting strips 5, which extend the entire length of opposite longitudinal sides of said sheets. Below the upper sheets 2, are sheets 6, the latter having perforations 7, 85 which are of decreased size with respect to the perforations 3, in the superposed sheets 2, for receiving the small ends of the eggs mounted in the perforations and supported thereby. On opposite longitudinal sides of 90 the sheets 6, flexibly formed by crease lines 8, are downwardly bent connecting strips 9, which are of less depth than the said strips 5, of the sheets 2, and which are connected to the said strips 5, so as to hold the sheets in 95 spaced relation to each other and united. Furthermore, the unitary tray structure is capable of being brought from operative to a folded position. The tray structure 1, is removably held within a box 10, of knock-down formation and comprises a bottom 11, flexibly connected side and end walls 12, and 13, respectively, and a cover 14, which is also flexibly connected to one of the side walls. Said side walls 12, have bendable tongues 15, adapted to engage slots 16, formed in the end walls 13, so as to hold the box 10, in an operative position to receive the tray structure 1. It is to be understood that this formation of box is merely shown for the sake of disclosing 110

a convenient receptacle in which the tray structure can be removably held as it can be a crate or the like, and, therefore, the same is not an essential feature of the invention, as 5 any well known construction of box, crate or the like may be employed as found desirable.

In Fig. 4, is shown a modification of the tray structure which discloses superposed sheets 2, and 6, having therein perforations 10 3, and 7, respectively, and interposed between the connecting strips 5, and 9, and opposite outermost sides of the united sheets are reinforcing strips 17, which project a distance above and below the said sheets 2, and 15 6, and in proximity to the upper edges of each of the outermost strips 17, flexibly formed by a crease line 18, is a flexible and inwardly bent flange 19, to engage a removable partition 20, (Fig. 7) having perforations 20 21, to receive the ends of the eggs. Said partitions 20, are provided at opposite sides thereof with crease lines 22, to make flanges 23, bent at right angles to the body of said partitions 20, and the same are adapted to 25 contact with the strips 5, and 9, at the outermost sides of said tray structure when the latter is mounted above another tray structure. It will be apparent that these tray structures can be stacked one upon another 30 with the interposed partitions 20.

Fig. 8, discloses a cover or top 24, having flanges 25, at right angles thereto on opposite sides of the same to slidably engage the flanges 23, of the tray structure and the 35 upper sheets 2, thereof, so as to form a closure for the tray structure at the upper end of the stack. It will be obvious that this cover 24, can be used for a bottom at the base of the stack of tray structures, as well as it can be 40 used for a cover or top. Also said cover 24, may be perforated to receive the ends of the articles if found desirable.

In Fig. 9, is shown a further modified form of the tray structure, which involves the 45 superposed sheets 2 and 6, having the perforations 3 and 7, respectively, and the interposed reinforcing strips 17, between the connecting strips 5 and 9, and the opposite outermost sides of the united sheets. Said reinforcing strips 17, project a distance above and below the said sheets 2 and 6, and in 50 proximity to the upper crease lines 18, just below the flexible and inwardly bent flanges 19, are inverted sheets 26, having perforations 27, conforming to and receiving the smaller ends of the eggs or the like articles. Said sheets 26, are provided with crease lines 55 28, to make upwardly bent flanges 29, one of which latter on each sheet 26, is connected to the reinforcing strips 17, and the other flange 60 is free therefrom, so that the eggs or other articles can be inserted in position in the perforations 3 and 7, in the sheets 2 and 6, respectively, then said sheets 26, are lowered upon

said articles which enter the perforations 65 therein and they are maintained in such lowered position by the removable cover 24, or the top of the receptacle or the like in which the tray structures are placed.

Having described the invention, what is 70 claimed is:—

1. A foldable tray comprising a plurality of superposed rows of perforated sheets, the sheets of the superposed rows being flexibly connected at their adjacent longitudinal 75 edges to form a unitary collapsible structure.

2. A foldable tray comprising pairs of superposed perforated sheets, each sheet having its opposite edges bent at right angles thereto, the edges of one sheet being connected to the edges of the adjacent and superposed sheets. 80

3. A tray of the class described comprising perforated sheets arranged in superposed parallel rows, and means flexibly uniting the 85 rows and sheets at their longitudinal edges to permit collapsing of the structure.

4. A foldable tray structure comprising a plurality of superposed perforated sheets, each having flexible connecting strips at its 90 longitudinal edges, and reinforcing means associated therewith, one edge of each uppermost sheet being disconnected to permit the raising of the sheet.

5. A foldable tray comprising spaced upper and lower perforated sheets hinged together along their opposite longitudinal edges to maintain said sheets in superposed relation with respect to each other and also 95 permit collapsing thereof one upon the other. 100

6. A foldable tray structure comprising a plurality of superposed perforated sheets, each having flexible connecting strips for uniting the same, reinforcing strips associated with the first mentioned strips, and 105 removable perforated partitions coöperative with the tray structure to allow the stacking of a series of the same.

7. A foldable tray structure comprising a plurality of superposed perforated sheets, 110 each having flexible connecting strips, reinforcing connecting strips associated with the first mentioned strips, a removable perforated partition coöperative with the tray structure to allow the stacking of the same, 115 and an imperforate top and bottom for said structure.

8. A foldable tray structure comprising a plurality of superposed perforated sheets, each having flexible connecting strips, reinforcing strips associated therewith, two of the latter having flanges at their upper edges, a removable perforated partition inserted between the said flanges and the uppermost sheets, and an imperforate top and bottom 120 for the said structure. 125

9. A foldable tray comprising perforated sheets, and means connecting the sheets at

their opposite longitudinal edges to normally hold said sheets in spaced relation to each other and permit collapsing thereof.

10. A foldable tray having perforated 5 sheets, and flanges at opposite longitudinal edges of each sheet, the flanges of one sheet being connected to the flanges of the other sheet to support the sheets in superposed relation to each other and permit collapsing 10 of the same.

11. A foldable tray comprising perforated sheets, and connecting strips at opposite longitudinal edges of each sheet, the connecting strips of one sheet being secured to 15 the connecting strips of the other sheet to hold the sheets in superposed position with respect to each other.

12. A foldable tray comprising perforated

sheets having hinged connecting strips throughout opposite edges thereof, the said 20 strips being united to normally hold the sheets in superposed elevated position with respect to each other.

13. A foldable tray comprising upper and lower perforated sheets, and means flexibly 25 connecting the sheets in spaced relation to each other, the lowermost sheet being held a distance removed from the bottom edge of said means.

In testimony whereof I have hereunto set 30 my hand in presence of two subscribing witnesses.

CHARLES FRANCIS ADAMS EDDY.
